UNITED STATES PATENT OFFICE.

HERBERT LYDEARD, OF SWINDON, ENGLAND.

SAFETY RETAINING MECHANISM FOR MINE CAGES, LIFTS, AND THE LIKE.

Application filed June 19, 1922. Serial No. 569,403.

To all whom it may concern:

Be it known that I, HERBERT LYDEARD, subject of the King of Great Britain, residing at 96 Beatrice Street, Swindon, Wiltshire, England, have invented new and useful Improvements in Safety Retaining Mechanism for Mine Cages, Lifts, and the like; and I do hereby declare the following to be a full, clear, and exact description in 10 the invention, such as will enable others skilled in the art to which it appertains to make and use the same.

This invention relates to a safety device for mine cages, lifts and the like which 15 will serve to arrest the downward motion of the cage or the like should the lifting cable or its equivalent break, and has for its object to provide a simple device which will be more efficient in action than existing 20 devices of this type.

According to my invention a guide member is provided having normally freely disposed therein a ball or balls adapted to be brought into engagement with a guide rope 25 or stay or the equivalent thereof in such manner as to arrest downward movement of the cage upon failure of the supporting means.

In carrying my invention into practice I 30 have appended hereto one sheet of drawings illustrating same wherein:—

Fig. 1 is a view showing my invention applied to a mine cage of known construction.

Fig. 2 is a diagonal sectional view of a 35 cage illustrating the embodiment of my invention.

Fig. 3 is a sectional view of a gripping device in the inoperative or free position.

Fig. 4 is a sectional view of a gripping 40 device in its operative or gripping position.

Referring to the drawings the cage 1 which may be of any known type is supported for lifting or lowering by means of a cable 2 connected to any suitable operating mechanism not shown, whilst the usual guide ropes or stays 3 are provided passing through suitable guides at each corner of the cage.

The cable 2 supports the cage by being 50 connected either directly or indirectly to a weighted member 5 slidably supported within a sleeve 6 firmly secured to the roof or other suitable part of the cage. For this purpose the upper end of the weighted member is provided with a loop 7 or other suitable means for the attachment of the cable

2 or a connecting piece 2^a. The upper end of this weighted member is also flanged at 8 to prevent it falling through the sleeve 6. Secured to the lower end of the weighted member is an enlarged base portion 9 which serves to support the cage and further gives additional weight to the member 5.

This base 9 is provided with a circumferential groove 10 adapted to receive the ends 65 of a number of fulcrumed levers 11 fulcrumed to brackets 12 depending from the roof or other suitable part of the cage. These fulcrumed levers are provided with horizontal arcuate ends 13 for this purpose 70 so that they fit freely in and conform to the curvature of the circumferential groove 10. The outer ends of the levers 11 are each formed with a bifurcated portion 14 which engages in a circumferential groove 15 provided around a plunger 16. Each of these plungers 16 is cylindrical and bored through its axial centre to receive a guide rope or stay 3 and has a sliding fit through a collar 17 screwed on to the base of a guide 4, 80 so that the plunger is mainly disposed within the guide 4.

The upper end of each of these plungers 16 is flanged at 18 so as to prevent it falling through the collar 17. This flanged portion 85 is tapered downwardly from the centre on its upper surface upon which freely rests a number of balls 19 which owing to the taper of the upper surface of the plunger tend to roll away from the guide rope or 90 stay 3, and normally i. e. when the cage is in working order, do not engage the said guide rope or stay but bear against the inner wall of the guide 4.

The guides 4 are of truncated cone formation having their walls converging upwardly so that should the plungers 16 move upwardly relatively to the said guides the balls 19 will be gripped tightly between the guide ropes or stays 3 and the inner walls of the 100 guides 4, thereby preventing movement of the guides and consequently the cage along the guide ropes or stays 3.

The operation of the device is as follows:—Normally the lifting cable 2 exerts 105 a pull upon the weighted member 5 so that the inner ends of the fulcrumed levers 11 are maintained in their uppermost position whilst the outer ends are maintained in their lowermost position so as to exert a pull 110 downwardly upon the plungers 16 in which position the balls 19 rest freely against the

inner walls of the guides 4 as clearly shown by Fig. 3 of the drawings. Should however the cable break or any other accident occur which would leave the cage unsupported by such cable, the weighted member 5 would immediately owing to its own weight move downwardly within the sleeve 6 and so move the outer ends of the fulcrumed levers 11 upwardly which will cause the plungers 16 10 also to move upwardly within the guides 4 and so grip the balls tightly between the guide ropes or stays 3 and the inner walls of the guides 4 whereby further downward motion of the cage will be immediately arrested.

It will be clear from the foregoing that the greater the weight of the cage and its contents the more positive will be the gripping action of the balls upon the guide ropes should the cable break, so that it will be no disadvantage from the point of view of the efficiency of the safety device to have excessive weights in the cage.

It will be apparent that in some cases a pair of gripping devices would serve the purpose instead of four.

Hitherto it has been proposed to provide a safety device comprising a guide member having a tapered inner surface in which is relatively movable a sleeve carrying a number of balls in its wall, this sleeve being adapted to be moved within the guide member by a weighted lever or spring, one end of the weighted lever being connected to the lifting cable.

What I claim is:—

1. The combination with guide stays, of a lift normally suspended by suitable tackle and mounted for movement along said stays, of means to arrest downward movement of the lift upon failure of its suspension means comprising a plurality of gripping devices one of which is associated with each guide stay, a plurality of levers each 40 of which is movable to predetermined raised and lowered positions and one of which is associated with each gripping device, said levers being operable when in raised position to hold said gripping devices released 45 with respect to said stays and being operable when in lowered position to cause said gripping devices to grip said stays, a guide sleeve secured to the lift, a weight guided by and movable through said sleeve to pre-

determined raised and lowered positions, 55 said weight having an annular groove, one end of each of said levers being disposed in said groove whereby all of the levers are movable simultaneously and correspondingly with the weight, said weight being maintained normally raised by said suspension tackle thereby to maintain the levers raised and the gripping devices released, so that upon failure of the suspension tackle said weight moves to lowered 60 position thereby to correspondingly move the levers and cause said gripping devices to grip the stays.

2. The combination with guide stays, of a lift normally suspended by suitable tackle 70 and mounted for movement along said guide stays, of means to arrest downward movement of the lift upon failure of its suspension means comprising a plurality of gripping devices one of which is associated with each guide stay, each of said gripping devices consisting of a hollow guide member provided with an interior upwardly tapering surface and having an associated guide stay passing therethrough, and a plunger 80 reciprocable within said guide member, said plunger having its upper end tapered downwardly and outwardly, and having a plurality of balls resting thereon, whereby upon upward movement of said plunger said 85 balls are forced inwardly into gripping engagement with the guide stay by the upwardly tapered wall of said guide member and whereby upon downward movement of said plunger said balls roll down the tapered upper end thereof and outwardly away from said guide stay; and a connection between the suspension tackle and each of said gripping devices whereby said plungers normally are held in a downward 90 position to maintain the balls out of gripping relation with the guide stays and whereby upon failure of the suspension tackle said plungers are caused to move upwardly thereby to cause the balls to grip 95 said stays.

In witness whereof I have signed this specification in the presence of two witnesses.

HERBERT LYDEARD.

In the presence of:—

G. HUGHES,
C. L. HUGHES.
